UNITED STATES PATENT OFFICE.

FRANK B. KENDRICK, OF LEBANON, NEW HAMPSHIRE.

TOOL-HOLDER

SPECIFICATION forming part of Letters Patent No. 633,852, dated September 26, 1899.

Application filed June 28, 1899. Serial No. 722,204. (No model.)

To all whom it may concern:

Be it known that I, FRANK B. KENDRICK, of Lebanon, in the county of Grafton and State of New Hampshire, have invented a new and 5 Improved Tool-Holder, of which the following is a full, clear, and exact description.

My invention relates to an adjustable pin-vise and tool-holder especially adapted for the use of dentists and jewelers.

10 The object of the invention is to construct a device of the character described that may be operated by one hand and in which spring-tempered jaws are provided that automatically open when released from the pressure 15 of a regulating device, the regulating device also serving to close the jaws upon the tool or object passed between them, and wherein further means are provided for subsequently locking the jaws in gripping or binding engagement with the article they carry.

The invention consists in the novel construction and combination of the several parts, as will be hereinafter fully set forth, and pointed out in the claims.

25 Reference is to be had to the accompanying drawings, forming a part of this specification, in which similar characters of reference indicate corresponding parts in all the figures.

Figure 1 is a side elevation of the improved 30 device. Fig. 2 is a longitudinal vertical section through the device, the clamping-jaws being in an open position. Fig. 3 is a longitudinal vertical section through the device, the clamping-jaws being shown as closed for 35 engagement with an object passed between them and not locked; and Fig. 4 is a plan view of the device.

The handle A of the tool is preferably made tapering, being largest at its lower or outer 40 end, and at said lower outer end the handle is provided with longitudinal ribs 10 or is otherwise roughened to afford a grip for the fingers. A ferrule B is introduced into the larger end of the handle A, and said ferrule 45 extends beyond the outer end of the handle and is provided with a collar 11, that has bearing against the said outer end of the handle, as shown in Figs. 2 and 3. The bore of the ferrule B is in two diameters, the lesser diameter being at the inner end of the ferrule, and at the lesser diameter of the bore of the ferrule a thread 12 is produced.

A clutch or clamping device C is employed in connection with the ferrule B, being adapted to enter the same. This clutch or clamping device consists of a tube 13, having an exterior thread at one end adapted to engage with the thread 12 in the ferrule, and the exterior diameter of the said tube 13 is less than the diameter of the larger portion of the bore 55 of the ferrule B, as is also shown in Figs. 2 and 3. The tube 13 of the clutch or clamping device is provided with longitudinal slots 14, that extend through the outer end or head of the said device. These slots are usually 60 four in number, although any desired number may be employed, and these slots divide the head D of the device into mating and opposing jaws 15. These jaws 15 are very similar to ordinary clutch-jaws, having straight 65 inner edges, and their outer surfaces being beveled or inclined from a point in their length upwardly and inwardly in direction of the center of the head and then from said point downwardly and inwardly, as shown at 70 16 in the drawings.

A regulating-sleeve E is used in connection with the clutch or clamping device C, and this regulating-sleeve is provided at its outer end with an interior taper 17, corresponding to 80 the lower tapered portion of the head D of the clutch or clamping device. The lower portion of the regulating-sleeve is enlarged in diameter, thus forming a shoulder 18, and at the inner end of the said regulating-sleeve a 85 roughened exterior or knurled surface 19 is formed, enabling the sleeve to be either turned by the fingers or to be given end movement. The inner end of the sleeve is mounted to slide over the outer projecting portion of the 90 ferrule B and a spring 20 is coiled around the tube or shank section of the clutch or clamping device C, which spring has bearing against the shoulder 18 of the sleeve and against the outer projecting end of the ferrule B. The 95 spring normally forces the regulating-sleeve E outward, thus normally holding the jaws of the head D practically together; but when the sleeve E is drawn in direction of the handle the jaws of the head D automatically separate, owing to the spring character of the material of the tube 13, of which they form a 100 part, as illustrated in Fig. 2.

The tool may now be passed into the space

between the jaws of the head D, and when said tool has been placed in position between said jaws the sleeve E is released and the spring 20 forces the sleeve outward and causes the jaws to close against the shank of the tool. The jaws are now locked upon the tool or article introduced between them by simply turning the sleeve E, the handle A being held stationary, and these objects can be accomplished by the use of one hand. Upon turning the sleeve E when in its initial position the frictional engagement between the outer end of the sleeve and the head D of the clamping device will cause the said clamping device to turn also, and when the sleeve is moved in one direction the clamping device will be screwed into the ferrule, and consequently the jaws of the head D will be drawn as far as possible into the outer end of the sleeve E. When the tool is to be released, the sleeve E is turned in an opposite direction, thus unscrewing the clamping device C from the handle and causing the jaws of the head D to open to a greater or less extent, and at the same time the sleeve E is carried away from the collar 11 of the ferrule. By drawing the sleeve E in direction of the handle the jaws of said head D will open to their full extent and the tool may be dropped out.

When the device is used as a pin-vise, an opening 21 is made longitudinally in the handle, extending from end to end, being in communication with the interior of the tube-section of the clutch or clamping device, and preferably the handle A is always provided with the longitudinal opening 21, so that the device can be used as an ordinary clutch for light work or as a pin-vise.

Having thus described my invention, I claim as new and desire to secure by Letters Patent—

1. A pin-vise comprising a handle, a ferrule in said handle and having an interior screw-thread, a clutch in the form of a slotted spring-tube having its rear end formed with an interior thread fitted to the thread in the

ferrule and a regulating-sleeve having sliding movement on the clutch and spring-pressed toward the outer or split end thereof, the said sleeve when pressed out on the clutch coming into frictional engagement therewith, whereby a turning of the sleeve will screw the clutch into or out of the ferrule, as and for the purpose set forth.

2. A pin-vise and tool-holder comprising a handle, a ferrule having a shoulder between its ends, and inserted in the end of the handle with the shoulder resting on the edge of the same, the inserted end of the ferrule being formed with an interior thread, a clutch in the form of a slotted tube inserted in said ferrule and having a threaded rear end engaging the thread of the ferrule and an inclined head and a regulating-sleeve slidably fitted on the outer end of the ferrule beyond the shoulder thereof and having its outer end inclined to correspond to the head of the clutch, the said sleeve being spring-pressed outward into frictional engagement with the head of the clutch, as and for the purpose set forth.

3. A pin-vise and tool-holder, consisting of a handle having an aperture extending through the same, a clutch or clamping device comprising a slotted spring-tube having a screw connection with said handle and terminating in jaws at its outer end, said jaws having their outer surfaces tapered from a given point between their ends upwardly and inwardly and downwardly and inwardly, a regulating-sleeve held to slide upon a portion of the handle and over the tube of the clutch or clamping device, one portion of the sleeve being arranged for frictional engagement with the said jaws, and a spring arranged to normally hold said portion of the sleeve in engagement with the said jaws, as described.

FRANK B. KENDRICK.
